Attys.

UNITED STATES PATENT OFFICE.

SANFORD L. CLUETT, OF TROY, NEW YORK, ASSIGNOR TO CLUETT, PEABODY & CO., INC., OF TROY, NEW YORK, A CORPORATION OF NEW YORK.

FOLDING MACHINE.

Application filed December 22, 1921. Serial No. 524,136.

To all whom it may concern:

Be it known that I, SANFORD L. CLUETT, a citizen of the United States, and resident of Troy, in the county of Rensselaer and 5 State of New York, have invented new and useful Improvements in Folding Machines, of which the following is a specification.

This invention relates to folding machines of the type having folding blocks moving 10 into and out of folding position in such manner that all parts of each block have like motion and more particularly to machines for folding collars and cuffs where the folding blocks are arranged in pairs synchronously to move obliquely across the 15 collar or cuff thereby simultaneously to fold both the sides and the ends of the blank.

The principal objects of the invention are to provide means for guiding the blocks into 20 and out of folding position more smoothly and accurately, to make machines of the character referred to more adaptable to articles of different shapes and styles, as for example to various styles of collars designed 25 to conform to the shape of the neck and shoulders of different wearers, and more satisfactorily to correlate the guiding means with the eccentric or similar means for actuating the folding blocks.

30 The invention comprises a member connected to the folding block at spaced points and movable in response to movement of the block along a predetermined path different from that of the block. The aforesaid member is preferably in the form of a slide 35 slidable longitudinally of the block and the connection between the block and member preferably consists of links pivoted to the block and member respectively. The guideway for said slide may be formed in a part 40 which is adjustable laterally, longitudinally or angularly (preferably in all of these ways) relatively to the position of the collar or other blank to be folded. Inasmuch as 45 an oscillatory movement of the folding block along an arcuate path, such as produced by an eccentric, is best suited to the folding of collars and cuffs and certain other articles, the aforesaid guiding means is preferably 50 adapted to permit such movement while restraining the block from substantial movement in any other direction. In the preferred arrangement each folding block is actuated and guided independently of the 55 other blocks, thereby to facilitate adjust-

ment of the parts and to afford a freer movement of the parts with a consequent amelioration of the tendency to wear and elimination of all tendency to bind if properly adjusted. 60

In order more clearly to illustrate the nature of the invention I have shown one concrete embodiment thereof in the accompanying drawings, in which:

Fig. 1 is a top plan view showing the 65 folding blocks retracted;

Fig. 2 is a section on line 2—2 of Fig. 1;

Fig. 3 is a view similar to Fig. 1 showing the folding blocks fully advanced; and

Fig. 4 is a detail view illustrating the 70 manner of adjustment of the folding blocks.

The construction of the particular embodiment of the invention chosen for the purpose of illustration is similar to that disclosed in my prior applications, Serial No. 509,382 75 and Serial No. 509,383 and comprises a frame 1, four folding blocks 2 carrying overlapping folding strips 3, a swinging arm 4 pivoted at 5, stationary guides 6 and 7 for holding the folding blocks down, a heated 80 plate 8 movable vertically in the frame 1 and eccentrics 9 for actuating the folding blocks.

According to the present invention each of the folding blocks 2 is connected to a slide 85 10 at spaced points by means of links 11 which are pivotally connected at their opposite ends to their block and slide respectively. The guideways for the slides are formed in members 12 which are held in 90 position on the frame 1 by means of bolts 13 passing through slots 14 in the member. The slots 14 are preferably wider than the bolts to permit adjustment of the members 12 transversely and angularly as well as longitudinally along the length of the slots, an angular adjustment being shown in Fig. 4. 95

As the eccentrics 9 swing the blocks inwardly both transversely and longitudinally of the position of the blank to be folded, the links 11 swing in like direction and the slides 10 slide in the guideways in response to the movement of the folding blocks owing to the different radii of eccentrics 9 and links 11, the slides moving toward the center of the machine in the inward movement of the blocks when the parts are adjusted as illustrated in Figs. 1 and 2. 100

By adjusting the position of the guideways 12 the positions of the folding blocks 110

may be varied, the folding blocks being maintained parallel to each other at all times with the adjustment shown in Figs. 1 and 3 and being held in angular relationship to each other with the adjustment shown in Fig. 4. The adjustment of the guideways 12 toward and from the folding blocks along the lengths of the slots 14 affords a quick and effective way of adjusting 10 the positions of the pivotal connections between the slide 10 and links 11 relative to the folding blocks, thereby to correlate the guiding means with the eccentric actuating means to afford the freest movement of the slides in their guideways as the folding blocks move inwardly and outwardly.

I claim:

1. A folding machine comprising a folding block, means for actuating said block, and means for guiding said block including a member connected thereto at spaced points only and movable in response to movement of the block along a predetermined path different from that of the block.

2. A folding machine comprising a folding block, means for actuating said block, and means for guiding said block including a member pivotally connected thereto by links at spaced points and movable in response to movement of the block along a predetermined path different from that of the block.

3. A folding machine comprising a folding block, means for actuating said block, and means for guiding said block including a member moving in a fixed guideway and connected to said block at spaced points and free to slide in response to movement of the block when the latter is actuated by said actuating means.

4. A folding machine comprising a folding block, means for actuating said block, and means for guiding said block including a slide pivotally connected to said block at spaced points and free to slide in response to movement of the block when the latter is actuated by said actuating means.

5. A folding machine comprising a folding block, means for actuating said block, and means for guiding said block including a slide parallel with said block and links pivotally connecting the slide and block at spaced points, the slide being free to slide longitudinally of the block in response to movement of the latter when actuated by said actuating means.

6. A folding machine comprising an elongate folding block, a guide member having a slideway extending longitudinally of the block adjacent thereto, a freely movable slide in said slideway, links pivotally connecting said block and slide at spaced points along the length thereof, said links being so disposed as to transmit movement from the

block to said slide, and means for moving 65 said block into and out of folding position, the parts being correlated to permit said slide to slide in its slideway while maintaining said block parallel to its folding position at all times.

7. A folding machine comprising a folding block, means for oscillating said block into and out of folding position, and means for guiding the block including a member movable along a predetermined path and 75 means having pivotal connection with the block and member respectively to maintain the block parallel to a fixed line in all positions while permitting oscillatory movement thereof.

8. A folding machine comprising a folding block, means including an eccentric for oscillating said block into and out of folding position along an arcuate path, and means for guiding the block including a 85 member movable along a normally fixed guideway and a link connection between the block and member arranged to cause all parts of the block to move along like paths.

9. A folding machine comprising a folding block movable into and out of folding position, a slide pivotally connected to the folding block and an adjustable member having a slideway for said slide, said member being adjustable to vary the movement 95 of said slide.

10. A folding machine comprising a folding block, means for moving the folding block into and out of folding position, a slide pivotally connected to the folding 100 block and movable thereby, and an adjustable member having a slideway for said slide, said member being adjustable transversely of the slideway.

11. A folding machine comprising a folding block, means for moving the folding block into and out of folding position, a slide parallel with said block and links pivotally connecting the slide and block at spaced points, the slide being free to slide longitudinally of the block in response to movement of the latter, and an adjustable member having a slideway for said slide, said member being adjustable to vary the movement 110 of the slide.

12. A folding machine comprising a pair of folding blocks adapted to move simultaneously and independently into and out of folding position, a slide pivotally connected to each block by spaced links and slidably 120 in response to movement of its associated block independently of movement of the other block, and means for actuating the blocks.

Signed by me at Troy, New York this 16 125 day of December 1921.

SANFORD L. CLUETT.
